DESIGN FOR A PIN OR ANALOGOUS ARTICLE

Sydell Grombecker, New York, N. Y.

Application August 22, 1941, Serial No. 102,986

Term of patent 3½ years

To all whom it may concern:

Be it known that I, Sydell Grombecker, a citizen of the United States of America and resident of the county, city, and State of New York, have invented a new, original, and ornamental Design for a Pin or Analogous Article, of which the following is a specification, reference being had to the accompanying drawing, forming a part thereof.

Fig. 1 is a front elevational view of a pin showing my new design; and

Fig. 2 is a side elevational view thereof.

I claim:

The ornamental design for a pin or analogous article, as shown.

SYDELL GROMBECKER.
